(57) **CLAIM**

We claim the ornamental design for a blank for a cigarette package, as shown and described.

DESCRIPTION

FIG. 1 is a top plan view of a blank for a cigarette package; FIG. 2 is a bottom plan view of the blank for a cigarette package of FIG. 1, a front elevation view, a rear elevation view, a right elevation view, a left elevation view, and a top perspective view of the blank for a cigarette package of FIG. 1 have been omitted because the blank for a cigarette package of FIG. 1 is thin and flat and no additional ornamental details would be visible in these views; FIG. 3 is a top plan view of another embodiment of the blank for a cigarette package of FIG. 1; and, FIG. 4 is a bottom plan view of the blank for a cigarette package of FIG. 3, a front elevation view, a rear elevation view, a right elevation view, a left elevation view, and a top perspective view of the blank for a cigarette package of FIG. 3 have been omitted because the blank for a cigarette package of FIG. 3 is thin and flat and no additional ornamental details would be visible in these views.
